Application July 21, 1944, Serial No. 545,938

8 Claims. (Cl. 49—9)

1

This invention relates to glassware forming machines, and the particular embodiment disclosed is particularly adapted to form narrow neck bottleware, although certain features of the machine will be recognized as applicable to the production of a wide range of glassware.

An object of the invention is to provide a machine including a blank or parison mold adapted to receive a gob of glass and in which the parison of the bottle is formed in inverted position; a finish or blow mold adapted to receive the parison in reverted position wherein the bottle is finished by blowing, the said molds being so disposed in respect of each other so that the parison may be transferred by removal from the parison mold in an arcuate path and set in the finishing mold without deformation of the parison.

Another object of the invention is to provide a machine in which a parison mold is supported in a horizontal plane and in a position to receive a gob delivered from a glass feeding machine, and wherein the parison is formed by suction and blowing, and a finishing or blow mold laterally offset from the parison mold and in an elevated horizontal plane in respect thereto with an intermediate transfer device whereby the parison is moved in an arcuate path from the parison mold to the finishing mold wherein the blowing of the bottle is completed.

Another object of the invention is to provide a novel transfer device in a machine of the class described whereby the bottom of the parison of the bottle is engaged solely by a suction head while in inverted position, and then moved to the blow mold in an arcuate path in such a manner as to be received therein in reverted position without deformation for final finish by blowing.

A general objective of the invention is to provide a machine of the class described in which the structure and operating parts of the machine are simplified while providing a highly efficient and accurately operating mechanism, that is capable of producing uniform and accurately formed glassware.

Additional specific novel features and advantages of the structure will be apparent from the following detailed disclosure thereof taken in connection with the accompanying drawings, in which:

Fig. 1 is a side elevation of the machine, certain parts being broken away;

Fig. 2 is a plan view;

Fig. 3 is a side elevation opposite to that of Fig.

3
Base or frame structure

In the embodiment of the invention illustrated in the drawings, the machine is shown as supported by a base, which comprises spaced transverse I-beams 10, cross-braced by tie rods 11. Upon the upper face of the I-beam supports is a base plate 12 having a form best shown in Fig. 2. The general contour of the plate, it will be observed, includes a rear portion, the sides of which converge to form a generally triangular section, and a forward section, the area of which is widened to afford a support for the parison mold, later to be described. It will be understood that the plate is securely bolted or welded to the sub-support in order to afford a rigid frame or base for the operating parts of the machine.

An integrally formed lug 13 projects rearwardly from the base plate 12 and supports a vertically extending standard 14 which is bolted thereto, the said standard having a series of three U-shaped brackets 15, 16 and 17 formed integral with the rear wall thereof. These brackets constitute supports for the cylinders of the air motors, and are in substantially vertical alignment but spaced at equally disposed horizontal elevations. There are two brackets 18 and 19 integrally formed with the front wall of the standard 14, spaced as shown best in Fig. 1. These brackets provide rear supports, respectively, for the opening mechanism for the transfer device and for the finish mold.

A pair of laterally spaced columns 20 and 21 are bolted to and supported by the base plate 12, said columns being mounted, respectively, at each side of the plate, but spaced inwardly from the front edge thereof. Each of the columns carries, at an elevation above the base plate, a bracket support 22, and 23, respectively, and upon these brackets is mounted a plate 24 constituting a support for the parts of the machine, as hereinafter explained.

The plate 24 is in the form best shown in Fig. 5 from which it will be understood that it comprises a central section 24a, lateral arms 24b, and forwardly extending arms 24c, having upwardly extending ears 24d, the latter constituting brackets for supporting a shaft for the transfer mechanism later to be described.

Parison forming device

The parison mold is of the sectional type, comprising mold segments 25 and 26. The mold halves are mounted for swinging movements to open and close the mold. There is a spaced pair of hinge straps 27, for each mold segment. The hinge straps are pivotally supported on a hinge pin 28, rigidly mounted near the front edge of the base plate 12, in order that the mold when closed extends forwardly beyond the said plate.

The mechanism for opening and closing the mold includes a yoke 29, the arms of which extend forwardly and are spaced, respectively, from the mold segments opposite the rear quadrant thereof. The end 30 of each arm is bifurcated, and is pivotally connected to a link 31 by a pin 32, which link, in turn, is pivotally connected with its mold segment, by an eccentric pin extending through spaced flanges 33 on the wall of each mold section.

The shank of the yoke 29 extends rearwardly and into a cylinder housing 34, and has a reduced portion that is embraced by a spring 35. The shank is held in adjustment by a nut 36, threaded on the end of the shank that extends through the rear wall of the cylinder. The housing 34 is preferably formed integral with a slide

5 member 37. The slide member is U-shaped in cross section and rides on a rail 38 that is T-shaped in cross section. The slide is held in place by gibs 39 mounted on either side thereof, and bolted thereto by bolts 40. The slide is supported by a bracket or table 41 secured to the plate 12.

The slide 37 is operated by an air motor 42, connected with the slide by a connecting rod 43, provided with a turnbuckle connection 44 for adjustment.

While an air motor is shown, it will be understood that other types of power means for reciprocating the slide may be employed, such as power driven cams.

It will be understood that the blank mold is alternately opened and closed to receive and release the parison in timed relation with the feed of the gob, and the transfer device for the parison from the parison mold to the finish mold.

The parison mold has a circumferential series of vertical passageways 45, extending upwardly from the lower edge of the mold segments, and said passages communicate with a semi-annular recess 46 in each mold section. A split neck ring 47 is mounted in the recess 46. The fit of the neck ring in the recess has sufficient clearance in order that communication between the recess 46 and the passages 45 is maintained.

30 A combination suction and blow head (Figs. 11 and 12) is mounted below the lower end of the parison mold. This head comprises a housing 48, which is supported by a bracket 49, rigidly connected with the front edge of the plate 12. The housing 48 is provided with a central bore 50 having an enlarged annular recess 51 from which a passageway 52 extends laterally and communicates with a conduit 53. A second annular recess 54 is formed in the housing 48, and extends radially from the central bore 50. A passage 55 is connected into said recess 54, which passage connects with a conduit 56 (Figs. 11 and 18). An annular series of passages 57 extend upwardly from the chamber 54, and communicate with a cylindrical recess 58 formed in the top of the housing 48.

45 In the bottom section of the housing 48 is a cylindrical chamber 59, having a lateral passage 60, which is connected with a conduit 61. The chamber 59 is closed by a head plate 62 bolted thereto which has a passageway 63 extending axially therethrough, which passageway communicates with a conduit 64.

50 A piston 65 is mounted in the chamber 59 and carries a piston stem 66 that extends through an axial bore 50 formed in the housing. The piston stem 66 has a bore 67 extending downwardly from the top wall thereof, and terminating about intermediate of its length. The lower end of the passage formed by the bore 67 communicates with an annular series of laterally extending passageways 68 and is adapted to be brought into and out of communication with the chamber 51 when the piston stem 66 is reciprocated by the movement of the piston 65.

55 The plunger (Fig. 13) comprises a base section 69, having a cylindrical cavity 70 in its lower wall adapted to fit over the upper reduced end of the piston stem 66, with which it is connected by a pin 71. In the upper wall of the chamber 70 is a series of obliquely extending passageways 72. A plunger plug 73 is formed integrally with the top wall of the base section 69.

60 A plunger ring shown in detail (Figs. 16 and 17) is mounted in the recess 58 in the upper wall of 70 the housing 48. This member comprises a base

section 14 and a flange 15. The base section 14 has an enlarged recess 16 in its bottom wall, and a series of upwardly extending diverging passageways 17. Above the flange 15 is a reduced portion 18 that develops into an enlarged head 19, having lower inclined walls 20. A series of passageways 21 extend laterally in crossed relationship through the inclined walls 20 of the head of the plunger ring, and communicate with a central bore 22. The top wall of the head 19 has a series of grooves 23 therein.

A brief summary of the operation of the suction and blow head follows.

In Fig. 11, the parts are shown in a position for blowing the hollow parison, and in Fig. 12 the parts are shown in the position when the mold is open. By reference to Fig. 11, if it be assumed that the baffle plate is in position to close the upper end of the parison mold and the mold sections closed, the plunger ring is then raised to the position shown in Fig. 11 by the action of closing the mold. This is because the lower mold opening has a circular side wall 24 that develops into an inclined wall 25. The inclined wall 25 cooperates by cam action with the inclined wall 26 on the plunger ring, so that initially before the mold receives the mold charge the plunger ring is lifted from its seat, as is shown in Fig. 12, to the position shown in Fig. 11.

The next operation is the admission of pressure through the conduit 27, which drives the piston 28 upwardly in the piston chamber 29 carrying the piston stem, and the plunger upwardly, and forces the plug of the plunger into the opening in the neck ring. This movement of the piston brings the passages 30 into communication with the chamber 31 which, in turn, is also in communication with the passage 32, the recess 33, the passages 34, and the passageways in the lower wall of the mold section 35.

Likewise, communication is established from the passageway 30 through the bore 31 to the passageways 32 in the plunger. When this adjustment has been effected, suction is then imposed upon the chamber 31 through the conduit 36, exerting a vacuum pull in the passageways described. This vacuum pull exerts itself around the neck ring through the passages 34, across the top wall of the plunger ring through the passages 33, and around the upper crown of the plug of the plunger in communication with the opening 32. This action draws a portion of the mold charge into closed contact with the neck ring, and compacts the charge in the neck of the parison.

When this operation has been accomplished, pressure is then established through the conduit 37, the passageway 38, and the chamber 39, against the upper head of the piston 28 forcing the piston stem downwardly, and thereby closing the communication between the passageway 30 with the chamber 31, and establishing communication with the chamber 40, the adjustment being as illustrated in Fig. 11. This action drops the plunger plug from the mouth of the mold opening.

Pressure is then imposed on the chamber 40 through the conduit 41 and the passageway 42, which pressure is exerted by way of the bore in the piston stem 43, the passages 44 in the plunger, through the recess formed by the inner wall of the plunger ring and the plunger, and through the axial bore in the plunger ring head, thereby imposing a pressure initially on the cavity formed by the plug of the plunger in the compacted

parison. The blow is continued sufficiently to complete the formation of the parison against the mold wall, and to expel the plastic glass from the interior of the parison, thereby completing the parison to a hollow form.

It will be understood, of course, that this operation occurs while the upper end of the parison mold is closed by a baffle plate, the construction and operation of which will now be described.

It should first be noted that the parison mold is so disposed in the machine that it is free to receive in its open upper end, a mold charge dropped from above. After the mold charge has been received in the open upper end of the parison mold, the opening is closed by the baffle plate by moving it from a position at the side of the mold to a position to close the mold.

The mounting of the baffle plate, and the means for operating it, comprise a standard 45 supported by the base plate 46. The standard supports

a cylinder 47, the upper part of which forms a piston chamber 48, closed by a cylinder head 49, and having a bottom wall 50. The lower part of the cylinder 47 forms a skirt in which there is a cam slot 51. Within the chamber 48 a piston 52 is mounted for reciprocation therein by air pressure. A conduit 53, through the cylinder head, serves to admit pressure to drive the piston downwardly and to exhaust pressure when the piston is moved upwardly. The conduit 54, entering the bottom of the cylinder, serves to drive the piston upwardly and to exhaust the chamber below the piston when the piston is driven downwardly. The piston carries a stem 55 that extends through the bottom wall of the piston chamber and into the lower part of the cylinder 47. An arm 56 extends laterally from the piston stem and projects outwardly through the cam slot 51. The arm 56 has bolted thereto a plate 57, to the outer extremity of which and on the under face thereof is secured a baffle plate or head shown in detail in Fig. 21. It will be understood that it comprises a plate 58 and a downwardly projecting head 59, having inclined side walls, and a convex bottom wall. The baffle head is dimensioned and contoured to fit into the upper mold opening 60 of the parison mold. The inoperative position of the baffle plate is clearly indicated in Fig. 5, from which it will be understood that it extends forwardly of the machine and laterally of the upper opening of the parison mold.

After the parison mold has received the mold charge, pressure is admitted through the conduit 53 to the piston chamber 48 driving the piston and its stem downwardly, thereby forcing the baffle plate arm downwardly and in a swinging motion laterally and backwardly until it registers with the mold opening 60 and continued downward movement of the piston firmly seats the baffle head in the mold opening.

The compacting and blowing of the hollow parison, in the manner as hereinbefore described, is accomplished while the baffle plate is in position, thereby sealing the opening and serving to form the bottom wall of the bottle.

After the parison has been formed, pressure is admitted through the conduit 54 to the chamber 48, which exhausts through the conduit 53. Pressure below the piston releases the baffle plate from the parison mold opening and returns it to its inoperative adjustment.

After this operation has been accomplished, the next operation is the engagement of the formed parison by the suction head of the transfer de-

vice, the structure and operation of which will next be described.

Transfer device

The transfer mechanism comprises a shaft 101 rigidly supported in the bracket 24d, formed on the plate 24. A casting, shown separately in detail in Figs. 24 and 25, is rotatably mounted in this shaft. This casting comprises a cylindrical section 102, carried by the shaft 101. A pair of spaced ears 103 extend upwardly therefrom, and provide means for connection with the power device.

The casting has a hollow extension 104 formed integrally with the section 102, and disposed at one side thereof, as shown in full lines in Fig. 24, and in section in Fig. 5. The extension 104 has an opening in its top wall, and a flexible suction conduit 105 is connected therein. A front section 106 integrally formed with the section 104 is cylindrical in form and is also hollow and in direct communication with the chamber formed in the section 104. The section 106 is forward of the shaft 101 and parallel therewith. The member 106 has a series of radial passages 107 through the wall thereof. A shaft 108 extends axially through the member 106. The shaft 108 is supported for rocking movement in a journal 109 at one end of the member 106 and at the other end in a boss formed as a part of the suction head. By reference to Fig. 5, it will be noted that the shaft 108 extends beyond each end of the section 106.

The suction head comprises a semi-cylindrical housing 110 with laterally extending flanges 111. This member is journaled on the member 106 and is recessed to form an annular chamber, which is in communication with the suction chamber formed in the members 105 and 106 by means of the passageways 107. A plate 112 is connected with the flanges 111 by bolts 113 that extend through flanged sleeves 114. Surrounding each of the sleeves 114 is an expansion spring 115 that fits between the flange at the top of each of said sleeves 114 and the top face of the respective flange 111. It will be noted that the lower end of each of the sleeves 114 is mounted in an opening formed, respectively, in the flanges 111, the diameter of which opening is slightly in excess of the external diameter of the sleeves 114, and also that there is a slight clearance between the central boss of the plate 112 and the opening in the lower wall of the member 110. Therefore, since the matching faces of the flanges 111 and the plate 112 are resiliently held together by the construction described, the plate 112 has a slight floating movement for centering the suction head in the opening of the parison mold.

On the bottom of the plate 112, and formed integrally therewith, is an extension 116 that has an annular flange 117, below which are inclined walls 118 dimensioned to fit in the opening in the upper end of the parison mold. The extension is preferably formed with a circular recess in its bottom wall between the edges of the wall 118, and in this recess is a plug 119, the lower wall of which is convex to extend downwardly into the mold opening. The plug 119 has an annular recess 120 therein, the lower walls of which are spaced to form passageways directly in communication with the cavity in the parison mold. The plug 119 is secured in the recess by a set screw 121, so that it may be removed for replacement or for cleaning. An angular series of passageways 122, formed through the upper wall of the plug 119 and through the wall of the plate

112, afford communication with the chamber formed between the members 106 and 110 so that, when the suction head is adjusted to close the parison mold top opening (Fig. 7), suction is directly impressed against the wall of the parison below the mold opening.

It will be understood that the suction head is brought into operation after the parison has been blown and the baffle plate removed. The operating connection for moving the suction head into and out of position includes a link 123 keyed to the shaft 108, and a nut 124 is threaded over the end of the shaft, said link 123 having a cam slot 125 therein that fits over the roller 126, supported on a stud shaft 127, which stud shaft, in turn, is rigidly carried in a bracket 128 supported by the plate 24. It will be understood that the shaft 108 also serves to hold the suction head on its mounting, as said shaft has a nut 129 on its left end that impinges against the end wall of the member 110 (Fig. 6) and keys the shaft thereto.

The power means for operating the suction head includes a slide 130 mounted on a rail 131, supported on the bracket 18 at one end, and by the plate 24 at the opposite end. The slide is mounted on the rail 131 in substantially the same manner as the slide for opening and closing the parison mold, as heretofore described.

The slide is also operated in a similar manner by an air motor 132 connected with the slide by a connecting rod 133 provided with a turnbuckle connection 134. The slide 130, however, has upstanding spaced ears 135, which connect one end of a connecting rod 136 therewith by a pivoted box joint 137. The connecting rod 136 may be provided with a turnbuckle connection 138 for adjustment purposes.

When the slide 130 is operated to the right (Fig. 40) the suction head is moved to position to close the upper opening of the parison mold. When the slide is reciprocated in the opposite direction, the suction head moves in an arcuate path finally bringing the parison into a position to be embraced by the finish mold (Fig. 23).

The stages of movement of the parison by the transfer device are diagrammatically illustrated in Figs. 26-28. In Fig. 26, the parison has started its arcuate movement forwardly and upwardly. In Fig. 27, the movement has been partially completed, and in Fig. 28 final movement to position for reception in the finish mold has been completed.

The transfer mechanism just described is an important and essential part of the present invention, as it obtains the advantage of permitting the hollow parison to be completed in the parison mold and the transfer effected by engaging the bottom of the parison solely by vacuum pull, and then, by means of the mechanism described, the parison is moved in a short arc so that it is reverted for reception in the finish mold. By forming the parison in inverted position and engaging the previously finished bottom wall of the parison with the plug 119 having a shape complementary to said bottom wall, the movement to the finish mold permits the heavy end of the parison to move on a short arc with the lighter end of the parison taking the longer arcuate path of movement. The parison is taken from the parison mold after it has sufficiently set, so that centrifugal forces are insufficient, because of the manner of transferring the parison, to distort the parison or to deform it in any way before it is received in the finish mold. The

advantages of the transfer mechanism will, therefore, be readily understood.

Finish mold

The finish mold, it will be understood, is located at an inset position from the front of the machine, and at an elevation so that, by a movement in an arc of substantially 180°, the parison is brought from its inverted position to a reverted position for reception in the finish mold. The finish mold itself is of orthodox construction comprising mold sections 139 and 140. The mold halves have recesses to receive and interlock with the extension 116 and its parts 117 and 118 of the transfer suction head. The mold halves are mounted for swinging movement to open and close the mold. There is a spaced pair of hinge straps 141. The hinge straps are pivotally supported on a hinge pin 142 by a plate 143 supported between the columns 20 and 21.

Inasmuch as the mechanism for opening and closing the finish mold is a substantial counterpart of the mechanism for opening and closing the parison mold, it is unnecessary to redescribe the structure, but similar parts have been designated as those parts were designated in the previous description with the suffix *a*.

The blow head for the finish mold is shown in section in Fig. 22, and the mounting therefor is best shown in Fig. 4.

The construction of the blow head is in general of standard construction but will be described in some detail for completeness of the disclosure.

The mounting for the blow head comprises a bracket 144, and a shaft 145 on which an arm 146 is adjustably supported, the blow head being connected directly to the outer extremity of the arm 146.

The blow head proper includes a housing 147, having a recess 148 in its upper end, which is closed by an end plate 149 bolted thereto, and forming a piston chamber. A piston 150 is mounted in the piston chamber and carries a piston stem 151, which extends downwardly in a bore 152 formed in the housing 147. The piston stem has an axial opening 153 therein, which extends substantially intermediate the length of the stem. This opening communicates with a radial passage 154 through the wall of the stem. This opening 153 and the passageway 154 provide communication with a passage 155 in the housing, into which is connected a pressure conduit 156 in which pressure is constantly maintained. Connected with the lower end of the valve stem is a blow head 157 having a recess 158 in its lower wall that fits over and seals against the opening in the blow mold. The head 157 is connected with the stem 151 by a coupling 159.

The chamber 148 has passageways 160 and 161 at opposite ends thereof, said passageways being connected with conduits 162 and 163 for the admission and exhaust of pressure from the piston chamber.

After the parison has been brought to position, and the finish mold closed, the blow head is moved to close the open end of the finish mold, and over the open end of the parison by admission of pressure through the conduit 163, which forces the piston and the piston stem downwardly carrying the head 157 into position. This downward movement of the piston stem brings the passage 154 into communication with the passage 155, connected with the pressure conduit 156.

There is a passage 164 in the head 157 in alignment with passage 153, and branch passages 165 in said head that provide direct communication with the open end of the parison. This provides for directly blowing the article to final form.

After the final blowing, the finish mold is opened and the article removed by any suitable takeout device.

Operation

The operation of the machine has been partially described in connection with the separate parts. An overall description of the operation will tend to clarify the disclosure and to further explain the sequence and synchronism of the operation.

The initial adjustment of the machine will be assumed to begin with the closing of the parison mold, with the baffle plate in open adjustment, and the transfer suction head in raised position, it being understood that the closing of the parison mold effects a primary adjustment of the suction and pressure head in the lower opening of the parison mold. When the machine is in this adjustment, there is a free vertical passage for the mold charge to enter the upper opening of the parison mold. When the mold charge has been received in the parison mold, the baffle plate is moved to closed adjustment in the manner already described. When the baffle plate is in position to close the parison mold, the plunger is raised and the suction or vacuum conduit is then opened, effecting the compacting of the mold charge at the neck end of the parison.

Following the compacting of the parison, the plunger is depressed, the suction or vacuum discontinued, and pressure is applied through the pressure head, as heretofore described. The baffle plate is then moved to open position.

These operations are timed to permit the parison to set by the formation of a skin or enamel in the manner well understood in the art.

The suction head of the transfer device is then moved over the upper opening of the parison mold, and suction is applied to engage the upper end of the parison, followed by an opening of the parison mold. The suction on the head of the transfer device is maintained, and the transfer device operated in the manner heretofore described to move the parison in the arcuate path, thereby presenting it in a position to be embraced by the open halves of the finish mold. The finish mold is then closed about the parison, the suction head of the transfer device serving as a closure for the lower opening of the finish mold, and suction on the head is thereupon preferably relieved. The parison then rests on the suction head, and projects from the top of the mold, as shown by Figs. 22 and 23. Thus the parison is given a length substantially equal to that of the finished ware. The finish preferably projects through the top of the blow mold, and is stabilized by interengagement therewith. The blow head is operated to close the upper end of the finish mold, and the final blow given to the parison to complete the article.

It will be understood that as soon as the parison is removed from the parison mold and the transfer device elevated to clear the vertical path to the open end of the parison mold, the parison mold is again closed and the operation described is continued in succession.

Reference to the diagrammatical Fig. 29 will clarify the operation of the entire machine. In

this view the movements of the principal parts are obvious from the arrows and legends thereon.

The three most important air valves, that is the blank mold blow valve A, the transfer vacuum valve B, and the blank mold vacuum valve C are mounted on the base plate 12 (Figs. 1 and 2). The control effected by these valves is clear from the drawings without additional detailed description.

While many of the parts of the structure have been described in specific detail, it will be recognized that changes and modifications in the structure may be made within the limits of the invention. It should be understood, therefore, that the invention is not to be limited by specific description beyond the scope of the claims.

What I claim and desire to secure by Letters Patent is:

1. In a machine of the class described, the combination with a parison mold having a mold cavity to form a glassware article in inverted position, the cavity extending downward through the top of the mold, means for compacting and blowing the parison to a hollow form located at the bottom end thereof, means to finish the top end of the inverted parison to form a bottom surface portion of the completed ware, and a finish mold adapted to receive the parison in reverted position, of a suction head adapted to engage the top end of the inverted parison while contained in the parison mold, and means for operating said head to remove the parison from the parison mold and to move it to present it for engagement by the finish mold in reverted position.

2. In a glass making machine for making hollow container ware, a first mold adapted to receive a gather of glass and to have the gather shaped into a parison having its bottom surface shaped to the final form of the ultimate glassware, suction head means interfitting with said finished bottom surface to hold the glass securely thereon by suction, a second mold spaced from the first mold, mechanism to move the interfitting means with the glass from the first mold to the second, said suction head means and second mold having complementary inter-locking shaping portions whereby the suction head fits into and interlocks with the second mold and forms a wall part therein, and means associated with the second mold at a location spaced from said wall part, to expand the remainder of the parison into the second mold.

3. In a machine for making glass bottles, a parison mold adapted to receive a gather of glass, said mold having neck-forming portions at the bottom of the parison mold and body-forming portions extending upwardly from the neck-forming portions, means to force the gather into the neck-forming portions to shape the neck of the bottle, means to force the glass into the body-forming portions to form a parison body, means movable relative to the mold, having a surface shaped to form a suction-engageable surface on the end of the parison opposite the neck, a suction head having a surface complementary to the suction-engageable surface on the parison, means to withdraw the movable means of the mold from the suction-engageable surface, and transfer mechanism including means to introduce the suction head surface against the suction-engageable surface of the parison, means to apply suction to the head to hold the parison to the head by the suction-engageable surface of the parison, a second mold spaced from the first, and the transfer mechanism including means to swing the suc-

tion head with the parison from the parison mold to the second mold, the swinging means having mechanism to invert it, and dispose it with the neck portion upwardly with respect to the second mold.

4. In a glass container forming machine, a first mold for making an inverted parison, the mold having parts at its bottom for forming the finish on the parison, removable parts at its top for forming a final surface on the parison, and means for applying the removable parts to the top of the mold and for withdrawing the same from the mold, a second mold for completing the container in upright position, and transfer mechanism, having a head interfittable with the final surface on the parison and suction means in the head for holding the parison onto the head, means for turning the transfer head and parison right side up and disposing it for enclosure in the second mold, and means for closing the second mold onto the parison while the parison is supported upon the transfer head, the head forming a bottom closure for the second mold.

5. In a glass container forming machine, a first mold for making an inverted parison, the mold having parts at its bottom for forming the finish on the parison, removable parts at its top for forming a final surface on the parison, and means for applying the removable parts to the top of the mold and for withdrawing the same from the mold, a second mold for completing the container in upright position, and transfer mechanism, having a head interfittable with the final surface on the parison and suction means in the head for holding the parison onto the head, means for turning the transfer head and parison right side up and disposing it for enclosure in the second mold, and means for closing the second mold onto the parison while the parison is supported upon the transfer head, the head forming a bottom closure for the second mold.

6. In a glass bottle making machine, a parison mold having means to form a hollow, inverted parison with a completed upper surface shaped to constitute a bottom surface of a completed bottle, a finish mold, and a transfer mechanism having a suction head interfittable with the said completed surface of the parison and suction means to cause the parison to be held to the suction head, means to swing the suction head approximately 180° to move the parison from inverted to upright position, and means to close the finish mold on the upright parison with the suction head forming a bottom closure for the finish mold.

7. In a machine for making glass containers, a first parison mold shaped to form an inverted parison of the container, and having means to form an upper end portion on the inverted parison that constitutes a bottom portion of the completed container, a finishing mold having an upright cavity shaped to form an upright container, means to engage the upper end portion of the inverted parison, which is to become the bottom of the container, and means to turn the engaging means with the parison, to revert it and dispose the parison upright, for reception in the finishing mold.

8. In a machine of the class described, a sectional parison mold having an open upper end adapted to receive a mold charge, and a neck ring

at its opposite end, a suction and blow head arranged at the lower end of the mold, means for applying alternate suction and pressure to the lower end of said parison mold, movable means for closing the upper open end of the parison mold for finishing an upper surface on the inverted parison to constitute a bottom surface portion of the completed ware, means for applying and withdrawing the movable means to the mold, a transfer device including a suction head having a surface to engage the finished upper surface of the parison in air sealed relationship, and operating means for said transfer device for reverting the suction head engaging the parison, and a finish mold in position to receive the parison at the end of travel of said transfer device.

9. In a machine for forming glassware including a parison mold having an upwardly open cavity to form an inverted parison, and a finish mold positioned in respect of said parison mold at an elevation thereto and offset laterally therefrom, means movable to and from the parison mold, to close the cavity thereof, said movable means having a portion shaped to form a surface portion on the upper part of the inverted parison that will be on the bottom of the completed ware, a transfer device for engaging and transferring

the parison from the parison mold to the finish mold, including a support adapted to swing in a path from the top of the parison mold to the bottom of the finish mold, a head carried by said support formed to engage the aforesaid surface portion on the parison by suction impressed on the upper end of the inverted parison and shaped to close with the finish mold and form a closure therefor, operating means for said support whereby the same is moved in a path to revert the parison from its position in the parison mold for reception in the finish mold.
